TIMEPIECE DIAL COVER

Peter R. Haas, Minusio, Switzerland, assignor to
Sindaco S.A.

Filed Jan. 22, 1975, Ser. No. 543,001

Claims priority, application Switzerland July 29, 1974

Term of patent 14 years

Int. Cl. D10—07

U.S. Cl. D10—132

FIG. 1

FIG. 2

FIG. 3

FIG. 1 is a front elevational view of a timepiece dial cover showing my new design;

FIG. 2 is a rear elevational view thereof;

FIG. 3 is a typical side elevational view thereof.

I claim:

The ornamental design for a timepiece dial cover, substantially as shown and described.
